UNITED STATES PATENT OFFICE.

WILLIAM HORACE SPEARS, OF NEW YORK, N. Y.

DESIGN FOR A CANE OR UMBRELLA-HANDLE.

SPECIFICATION forming part of Design No. 32,354, dated March 20, 1900.

Application filed February 6, 1900. Serial No. 4,284. Term of patent 31 years.

To all whom it may concern:

Be it known that I, WILLIAM HORACE SPEARS, a citizen of the United States, residing at the city of New York, borough of 5 Queens, in the county of Queens and State of New York, have invented and produced a new and original Design for a Cane or Umbrella-Handle, of which the following is a specification, reference being had to the accompanying drawing, forming a part thereof, in which is represented a side elevation of a handle embodying the features of my design.

The design consists in alternate plain and fluted panels A and B, the plain panels being circumferentially continuous and arranged in 15 the same longitudinal plane.

I claim—

The design for a cane or umbrella-handle herein shown and described.

WILLIAM HORACE SPEARS.
